UNITED STATES PATENT OFFICE.

DELBERT F. BRATTON, OF JOHNSONVILLE, ILLINOIS.

BACK CONNECTING-ROD WRENCH FOR FORD MACHINES.

Application filed April 11, 1921. Serial No. 460,298.

To all whom it may concern:

Be it known that I, DELBERT F. BRATTON, a citizen of the United States, residing at Johnsonville, in the county of Wayne and 5 State of Illinois, have invented certain new and useful Improvements in a Back Connecting-Rod Wrench for Ford Machines; and I do hereby declare the following to be a full, clear, and exact description of the invention, such as will enable others skilled in 10 the art to which it appertains to make and use the same.

The object of the invention is to provide a simple and convenient tool for tightening 15 the back connecting rods of automobiles of the Ford type, which rods are inaccessible to the ordinary wrench and involve difficulty in the tightening thereof which requires the operator to resort to numerous 20 convenient expedients or else leave the rods in a loose condition until the aid of a machinist can be secured; and with this object in view the invention consists in a device of which a preferred embodiment is illustrated 25 in the accompanying drawings, wherein:

Figure 1 is a plan view of a wrench designed especially for the tightening of back connecting rods.

Figure 2 is a side view of the same.

Figure 3 is a sectional view showing one of the latches in engaging relation with a pawl to provide for the rotation of the socket in one direction.

Figure 4 is a detail view of a detachable and interchangeable wrench head adapted to be used in connection with the tool.

Figure 5 is a view of a modified form of wrench head and ratchet socket wherein the 40 shank of the former is round instead of angular or irregular as shown in Figures 1 to 4 inclusive.

Figure 6 is a plan view, and

Figure 7 is a side view of a modified form 45 of wrench showing different means for locking the pawls alternately in their inoperative positions.

Figure 8 is a transverse sectional view taken in the plane of the locking ring.

Figure 9 is a detail view of the locking 50 ring, detached.

The wrench consists essentially of a shank 10 having an offset handle 11, the body portion of the handle being disposed in substantial 55 parallelism with the shank and connected therewith by an obliquely dis-

posed offset 12 which affords the required leverage in the manipulation of the connecting rods without obstructive contact with adjacent portions of the machine frame, and 60 in a bearing 13 in the end of the shank which is bifurcated as shown is mounted a ratchet socket 14 having an angular or cross sectionally irregular seat 15 for the reception of the stem 16 of a head 17 having any suitable form and size of nut engaging seat or socket, the head being interchangeable to adapt it to fit any desired size of nut or bolt head.

The teeth of the ratchet are of the square 70 shouldered form for engagement by either of a pair of dogs 18 pivotally mounted as at 19 in the bifurcation of the shank for terminal engagement alternately with the teeth of the ratchet and yieldingly held in 75 engaging position by springs 19'. Also in connection with the dogs are latches 20 slidingly mounted in suitable guides 20' on the shank for engagement with the rear or tail portions of the dogs to provide for 80 holding one or the other thereof out of engagement with the ratchet to permit of the latter being rotated in the opposite direction.

In the modified construction illustrated in Figure 5 the head 22 is provided with a 85 round shank 23 for engaging the round seat 24 in the ratchet member 25, a pin 26 being employed to prevent independent rotation thereof.

In the modified form shown in Figures 6 90 to 9 inclusive the means for securing one of the dogs 27 out of engaging relation with the ratchet 28 consists of a ring 29 revolvably mounted upon the shank 30 and having an internally cam-faced ear 31 adapted to be 95 brought into operative relation with the inner or tail end of the dog to be retracted. Obviously the reversal of the wrench, to adapt it to be used to turn either a right hand or a left hand nut or bolt may be effected 100 simply by turning the ring through a half revolution.

By reference to Figure 4 it will be seen that the socket head 17 is removably secured to the ratchet socket 14 by means of a spring 105 pressed ball ratchet 16^a carried by the stem 16 and engaging in a depression 16^b in the wall of the seat 15 of the ratchet socket 14.

Having thus described the invention, what I claim is:—

A tool of the class described having a shank, a ratchet head journaled thereon,

pawls to engage and disengage said head pivoted on said shank, said shank having a tongue disposed intermediate said pawls, leaf springs having straight arms engaging 5 opposite sides of said shank, longitudinally curved portions returned from said arms, said pawls having extremities overlapping one end of said springs and walls engaged by and corresponding to the curvature of 10 said returned portions whereby the springs will urge the pawls at one end into engagement with the head and are held against displacing movement toward said head with

said springs serving to normally project the pawls at the other end beyond the outer 15 surface of the shank, and means movable along the shank to depress the latter ends of the pawls one at a time whereby one pawl is maintained in a released position, while the other pawl is in an operative position. 20

In testimony whereof I affix my signature in presence of two witnesses.

DELBERT F. BRATTON.
